UNITED STATES PATENT OFFICE.

GEORGE E. PETERSEN, OF BRISTOL, PENNSYLVANIA, ASSIGNOR TO WILLIAM H. GRUNDY COMPANY, INC., OF BRISTOL, PENNSYLVANIA, A CORPORATION OF PENNSYLVANIA.

LIQUID-FEED RECEPTACLE.

Application filed March 21, 1924. Serial No. 700,903.

To all whom it may concern:

Be it known that I, GEORGE E. PETERSEN, a citizen of the United States, and a resident of Bristol, county of Bucks, State of Pennsylvania, have invented a certain new and useful Improvement in Liquid-Fee Receptacles, of which the following is a specification.

The present invention relates to liquid feed receptacles, and more particularly to a receptacle designed and arranged to supply oil emulsion or any other liquid or flowing material in uniform regulated quantities.

Some of the objects of the present invention are to provide an improved receptacle for feeding liquid to a material or to any other point of use in regulated quantities; to provide a receptacle for feeding liquid uniformly and continuously throughout a period of operation; to provide means operating in conjunction with a liquid feed receptacle for varying the overflow level of the liquid contained therein; to provide an improved liquid feed receptacle whereby all parts thereof are readily accessible for cleaning and replenishing purposes; to provide a liquid feed receptacle arranged to have a continuous tilting action to discharge the liquid therein at a predetermined uniform rate; to provide an improved liquid feed receptacle wherein the shape of the receptacle is such as to produce a constant uniform supply of liquid regardless of whether the receptacle is full or approaching an empty condition; to provide means for feeding a liquid uniformly and continuously regardless of the viscosity of the liquid or its temperature as influenced by the surrounding atmosphere, or the temperature in which it is used; and to provide other improvements as will hereinafter appear.

In the accompanying drawings, Fig. 1 represents a front elevation of an emulsion or liquid feeding machine embodying one form of the present invention; Fig. 2 represents an elevation of one end of the machine; Fig. 3 represents an elevation of the other end of the machine; Fig. 4 represents a rear elevation of the machine; and Fig. 5 represents a section on line 5—5 of Fig. 1.

Referring to the drawings, one form of the present invention comprises a liquid supply receptacle or reservoir 10, formed by end walls 11 and 12, a front wall 13, and

a bottom 14 which is curved rearwardly 55 from the wall 13 and upwardly to join the upper edges of the end walls 11 and 12. This construction forms a receptacle with a transverse section having the general configuration of a sector of a circle, though 60 preferably it is slightly greater than a quadrant. However, this is a matter of design, and the invention is not limited to any definite size of sector.

In order to mount the receptacle 10 so that 65 its liquid contents can be discharged by way of its open top construction, it is mounted for swinging movement on a rock shaft 15 which extends between the upper front portions of the walls 11 and 12 and has its 70 projecting ends journaled respectively in arms 16 of end standards 17, which also carry rearwardly extending arms 18 for a purpose to be later described. This shaft 15 forms an axis of rotation for the receptacle 10 and it is so located as to be radially equidistant from the curved bottom 14. In other words, the center of curvature of the bottom 14 is coincident with the axis of rotation of the receptacle 10, so that there is 75 80 a uniform movement or change of the liquid contents of the receptacle 10 whenever the latter is turned on its axis.

To discharge the contents of the receptacle 10, one or more discharge outlets 20 are 85 formed by recessing the top edge of the front wall 13 so as to open into an inclined lip chute 21 or chutes. In the present instance, the receptacle is of the duplex type, being subdivided by a partition 22 into two 90 separate receptacles and hence two outlets 20 with attached chutes 21 are shown, so it will be understood that the invention is broadly to a single receptacle to which as many like units may be added as are required to serve the particular purpose to 95 which the device is applied.

As a means for causing the receptacle 10 to tilt so that it discharges its contents at a uniform predetermined rate, a rack 23 is 100 fast to and extends substantially throughout the width of the bottom 14 and in mesh with a pinion 24 fixed to a shaft 25 which is journaled in the standard arms 18. Motion is transmitted to the shaft 25 by any 105 suitable driving means, such for example as a worm wheel 26 fast on the shaft 25 and in mesh with a worm 27 on a spindle 28

which is journaled in brackets 30 secured to the standard 17. Preferably, the spindle 28 is arranged to be connected to a driven stub shaft 31 through a clutch 32 whereby the worm 27 with its coating parts can be disconnected from the main driving means, so that the receptacle 10 can be tilted independently thereof for replenishing, cleaning, or any other purpose. The stub shaft 31 carries a worm wheel 33 in mesh with a worm 34 on a shaft 35, which carries a pulley 36 driven from any suitable source at a speed to properly give the tilting action necessary to proportion the feed of liquid for the purpose intended.

For the purpose of causing the feed of the liquid to cease when the machine with which the receptacle cooperates comes to a stop, the shaft 15 carries one or more inwardly extending arms 37, the number depending upon the number of receptacles in use, there being one for each, each of which has a depending screw member 38 carrying a liquid displacing body or float 40. Under operating conditions, the shaft 15 is in a position to lower the float 40 into the liquid a sufficient amount to cause the liquid level to rise to the overflow level of the discharge outlet 20. To change the overflow level for inoperative conditions, the shaft 15 is connected by a crank arm 41 with a rod 42 which is connected to a pivoted bell crank 43, the other end of which is arranged in the path of two trip lugs 44 and 45 on the throw-off rod 46 of the machine with which the liquid feed is used.

In the operation of the liquid feed the receptacle 10 is placed in its initial starting position and filled with the desired emulsion or other liquid to be fed therefrom, and in such a position the surface of the liquid is at level just below the line of the discharge outlet 20 and consequently no liquid flows from the receptacle. When it is desired to start the feeding, the rod 42 is moved in the direction to cause the float 40 to lower the required distance into the body of the liquid so that it displaces as much of the liquid as is necessary to raise the level to overflow relation with respect to the discharge outlet 20, and thereupon the liquid flows by gravity down the discharge chute 21 and flows or drips from the end thereof to the point of application to the material or goods which are to be impregnated or moistened with the liquid contents. Simultaneously with the lowering of the float 40, the power drive is thrown into engagement and motion transmitted to the shaft 25, and thence by way of pinion 24 to the rack 23 on the bottom of the receptacle 10. With the starting of this feed the pinion begins to slowly rotate the receptacle 10 in a direction to tilt the receptacle about its discharge edge as an axis, and therefore insures a con-

tinuous feeding of the liquid to the discharge outlet 20. This feeding of the liquid can be controlled by varying the speed of rotation of the shaft, and it is customary to have such a speed relation between the shaft and the feeding speed of the material to which the liquid is to be applied so proportioned as to supply exactly the amount of liquid required for moistening the material. The control of the feeding is such that in case it is necessary to discontinue the feeding of the material to the machine or stop that machine for any purpose the feeding from the receptacle 10 will also automatically cease at this time as well as drip from the end of the discharge chute. This takes place because upon the stopping of the material feeding machine, the float or floats 40 will be automatically lifted out of the liquid in the receptacle 10 so that the level therein immediately falls by an amount equal to the volume of the aforesaid float, and this may be of course calculated with an exactness which definitely gives a predetermined lowering of the level below the mouth of the discharge outlet 20. Since the tilting feed of the receptacle also discontinues upon the stopping of the machine which feeds the material, there can be no further discharging of liquid until the aforesaid material machine again comes into action, and as soon as this happens there is an automatic return of the float into the liquid and the level thereof raised to the discharge point.

It will now be apparent that a complete unitary liquid feeding machine has been provided wherein it is possible to definitely proportion the liquid flow in accordance with the controlling conditions and also maintain such proportioned flow as a uniform continuous one. It will also be evident that since the receptacle for the liquid is of open top construction it can not only readily be replenished with fresh liquid when necessary but also it is possible to have access to its interior for cleaning purposes without dismantling any parts of the machine or removing covers or other accessories generally forming a part of liquid feeding apparatus.

In connection with the ordinary closed top liquid feeding devices, it is necessary to shut down the machine with which the feeding device is used and remove many parts in order to gain access to the interior of the liquid receptacle. This makes it exceedingly difficult to readily change from one form of liquid to another because it is practically impossible to completely drain the contents of the receptacle, and unless the entire structure is dismantled the receptacle cannot be cleaned to receive the new or different type of liquid.

While in the foregoing description there is a liquid feed device applicable to general

use and adaptable to many industries, it is desired to point out that the receptacle of the present invention is more particularly designed for use as an emulsion feed in the preparation of wool or any other material to be used in the textile industry, but it is to be understood that this is merely one use, and broadly considered the invention is equally applicable to the feeding of other liquids or solutions or for the purpose of feeding any material which is capable of a flowing or pouring feed. To those acquainted with the art, it is well known that in the worsted combing and spinning industry the wool and tops are treated with an oil or emulsion to facilitate the working process. This emulsion or oil treating of the wool has heretofore been carried out by cumbersome liquid feeders, involving the use of massive gravity controlled bodies or rotatable roll feeds which neither proportion nor uniformly control the feeding of the liquid to the wool. By the present invention, however, the defects and disadvantages of emulsion feeders are entirely overcome and eliminated, and a simple, compact feeding receptacle provided, the shape of which is substantially that of a quadrant so that the mass of liquid contained within the receptacle has a constant dimension with respect to the discharge outlet, and consequently delivers a uniform quantity of liquid to the discharge outlets and one which is continuous from full tank capacity until it is empty. Furthermore, by the present invention, the interior of the receptacle is accessible at all times, and its contents can therefore be entirely removed or completely drained whenever desired for the purpose of substituting another liquid without disconnecting the device from the machine or taking it apart to make the necessary change. It will further be evident that the device of the present invention operates efficiently and equally well for light or heavy liquids and so functions regardless of the viscosity of the liquid. This feature is important because the viscosity of many liquids changes with changes of temperature, and consequently in prior types of feeding devices such change in viscosity immediately effects a change in the rate of feeding, but in the receptacle of the present invention it is immaterial whether or not there is such a change in temperature as to alter the viscosity of the liquid, since this is automatically taken care of and the feeding maintained uniform throughout the operation.

Although but one form is shown in which this invention may be embodied, it is to be understood that the invention is not limited to any specific construction, but might be applied in various forms without departing from the spirit of the invention or the scope of the appended claims.

Having thus described my invention, I claim:

1. In a liquid feed mechanism, a receptacle mounted for tilting movement and having a discharge outlet, means for maintaining a constant liquid level area for all tilted positions of said receptacle, and means for tilting said receptacle to cause liquid to flow from said outlet. 70
2. In a liquid feed mechanism, a receptacle mounted for tilting movement and having a discharge outlet, said receptacle having one bounding wall equidistant at all points from the axis of rotation of said receptacle, and means for tilting said receptacle to cause liquid to flow from said outlet. 75
3. In a liquid feed mechanism, a receptacle mounted for tilting movement and having a discharge outlet in close proximity to the axis of rotation of said receptacle, said receptacle having one bounding wall equidistant at all points from said axis of rotation, and means for tilting said receptacle to cause liquid to flow from said outlet. 80
4. In a liquid feed mechanism, a receptacle mounted for tilting movement and having a discharge outlet, means for maintaining a constant liquid level area for all tilted positions of said receptacle, and means for tilting said receptacle at a predetermined uniform rate to discharge the liquid contents thereof. 90
5. In a liquid feed mechanism, a receptacle having one bounding face of arcuate form, means forming an axis of rotation 100 for said receptacle coincident with the axis of said arcuate face, a discharge outlet for said receptacle located within the arc of travel of said receptacle and arranged to discharge under tilting movement of said receptacle, and means for tilting said receptacle. 105
6. In a liquid feed mechanism, an open top receptacle having one bounding face of arcuate form, means forming an axis of rotation for said receptacle coincident with the axis of said arcuate face, a discharge outlet for said receptacle located within the arc of travel of said receptacle and arranged to discharge under tilting movement of said receptacle, and means for tilting said receptacle. 110
7. In a liquid feed mechanism, a receptacle mounted for tilting movement and having a discharge outlet, means for maintaining a constant liquid level area for all operating positions of said receptacle, means for tilting said receptacle to cause liquid to flow from said outlet, and means independent of said tilting means for varying the level of the liquid contents with respect to said discharge outlet. 120
8. In a liquid feed mechanism, a receptacle mounted for tilting movement and having a discharge outlet, means for maintaining 130

- ing a constant liquid level area for all operating positions of said receptacle, means for tilting said receptacle to cause liquid to flow from said outlet, and means including a liquid displacing device for varying the level of the liquid contents with respect to said discharge outlets.
9. In a liquid feed mechanism, a receptacle having one bounding face of arcuate form, means forming an axis of rotation for

said receptacle coincident with the axis of said arcuate face, a discharge outlet for said receptacle lying substantially along said axis of rotation, and means for tilting said receptacle.

Signed at Philadelphia, county of Philadelphia, State of Pennsylvania, this 17th day of March, 1924.

GEORGE E. PETERSEN.
